UNITED STATES PATENT OFFICE

164,962

BOTTLED DRINK COOLER

Warner Schumacher, Kansas City, Mo., assignor
to The Vendo Company, Kansas City, Mo., a
corporation of Missouri

Application July 31, 1950, Serial No. 11,495

Term of patent 14 years

(Cl. D67—3)

To all whom it may concern:

Be it known that I, Warner Schumacher, a citizen of the United States, residing at Kansas City, in the county of Jackson and State of Missouri, have invented a new, original, and ornamental Design for a Bottled Drink Cooler, of which the following is a specification, reference being had to the accompanying drawing, forming a part thereof.

Fig. 1 is a perspective view of a bottled drink cooler, showing my new design; and

Fig. 2 is a side elevational view of the bottled drink cooler.

The characteristic features of applicant's design reside in the embossed panel section containing the centrally disposed window.

I claim:

The ornamental design for a bottled drink cooler, as shown and described.

WARNER SCHUMACHER.
